UNITED STATES PATENT OFFICE.

CHARLES B. STRETCH, OF BROCKTON, MASSACHUSETTS.

FRINGE AND METHOD OF MAKING.

Application filed July 21, 1926. Serial No. 123,902.

The invention relates to textile fringes and essentially to a woven fringe and method of making it.

According to the ordinary method of weaving these fringes, a blank is formed of warp and weft threads, and comprises separate woven body portions joined by spaces in which the warp is continued and the weft is omitted as a filling, the weft thread being floated between these body portions. The portion or portions of the blank in which the weft is thus omitted is equal to twice the length of the fringe so that when cut through the middle the fringe will hang from the point at which the weft thread was last introduced into the body portions as a filling.

Great difficulty has been encountered in the making of these fringes on account of the tendency of the weft to ravel from the body portions, and the object of the invention is to provide means whereby during the weaving this trouble may be overcome without necessity of afterward stitching or tying the weft thread at the point from which the fringe hangs.

The invention can best be seen and understood by reference to the drawings in which—

Figure 1 shows in enlarged plan a portion of a blank or strip of fringe-forming fabric embodying the invention, and

Fig. 2 a face view of a piece of the fringe.

Referring to the drawings:—

1 represents the woven body portion of the fringe composed of warp and weft threads 2 and 3, respectively, the weft thread acting as a filler for the warp in the usual manner. From this body portion 1 the fringe 4 extends formed by extending the warp threads of the body portion and omitting the weft thread from all but a few of the warp threads thus extending, as will presently be described, the fringe then hanging from the edge of the body portion where the weft was last introduced.

As just noted the weft is omitted from a majority or all but a few of the warp threads thus extending to form the fringe, but the weave of the weft is continued beyond the edge of the body portion from which the fringe hangs through a few of the warp threads extending to form the fringe, forming a woven section 5. This weave of the weft thread is continued for some little distance beyond the edge from which the fringe depends but preferably not to the

outer edge of the fringe. It functions to prevent the weft from ravelling from off the edge of the body portion from which the fringe depends, and its effectiveness for this purpose is increased by tightening the weft onto the warp threads through which it is woven as shown in Fig. 2, this tightening being effected by a pull on the loose end 6 of the weft causing the weft to tighten onto the few threads through which it is woven when all tendency for the weft to ravel is eliminated inasmuch as there is no tendency for the weft thread to loosen from the warp threads around which it is drawn.

This forms a very efficient method for preventing the ravelling of the weft and does not in any way disfigure the fringe, inasmuch as the few threads through which the weft is woven and around which it is drawn become lost in the fringe.

To form the fringe by the continuous weaving of a blank, a body portion 1 is first woven. From this body portion 1 the warp threads are extended or floated to a second body portion 1 and the weft is omitted from a majority of the warp threads thus extended or floated. The weft is continued through the remaining few of the extended warp threads to form a woven section 5 extending for some appreciable distance beyond the edge of the body portion from which the warp threads are being extended or floated. From the section 5 the weft thread is floated to form another woven section 5 with the same few warp threads as before and afterward the weave of the weft continued in forming a filling for the second body portion 1 of the blank, and so on.

The extension of the warp and omission of the weft, excepting as noted above, is for a distance twice the length of the fringe so that when cut through the middle the fringe will hang from the opposite edges of the respective woven body portions from which the warp is extended or floated and along which the weft was last introduced as a filler.

After the weaving of the blank the floating warp and weft threads are severed between the respective body portions and then the weft thread is tightened onto the warp threads through which it is woven in forming the respective sections 5 of the weave by a pull on the loose cut ends 6 of the weft thread.

Having thus fully described my invention, I claim and desire to secure by Letters Patent of the United States:—

1. A woven fringe having a body portion comprising woven warp and weft threads and a fringe composed of warp threads extended beyond said body portion with the weft thread omitted from a majority of the fringe-forming warp threads but the weave of the weft thread continued through the remaining few of the fringe-forming warp threads for preventing the weft thread from raveling.
2. A woven fringe having a body portion comprising woven warp and weft threads and a fringe composed of warp threads extended beyond said body portion with the weft thread omitted from a majority of the fringe-forming warp threads but the weave of the weft thread continued through the remaining few of the fringe-forming warp threads for a distance less than the length of the fringe.
3. A woven fringe having a body portion comprising woven warp and weft threads and a fringe composed of warp threads extended beyond said body portion with the weft thread omitted from a majority of

the fringe forming warp threads but the weave of the weft thread continued through the remaining few of the fringe-forming warp threads and tightened thereon.

4. A woven fringe blank comprising separate body portions of woven warp and weft threads and fringe-forming portions composed of warp threads extended between said separate body portions with the weft thread omitted from a majority of the fringe-forming warp threads but the weave of the weft thread continued through the remaining few of the fringe forming warp threads.

5. A woven fringe blank comprising separate body portions of woven warp and weft threads and fringe-forming portions composed of warp threads extended between said separate body portions with the weft thread omitted from a majority of the fringe-forming warp threads but continued through the remaining few of the fringe-forming warp threads to form woven sections immediately adjacent said body portions with the weft thread floated between said sections.

CHARLES B. STRETCH.
